CLAIM

The ornamental design for a drinking container, as shown and described.

DESCRIPTION

FIG. 1 is a perspective top view of a new design for a drinking container;

FIG. 2 is a perspective bottom view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof; and,

FIG. 9 is a cross-sectional view showing a section taken along line 9-9 of FIG. 5.

The broken lines in the drawings depict portions of the drinking container that form no part of the claimed design.
